UNITED STATES PATENT OFFICE.

PORTEUS R. CUNNINGHAM AND CHARLES H. HOWLAND-SHERMAN, OF WASHINGTON, DISTRICT OF COLUMBIA.

INVERTIBLE FLUID-BATTERY.

SPECIFICATION forming part of Letters Patent No. 602,616, dated April 19, 1898.

Application filed February 20, 1897. Serial No. 624,423. (No model.)

To all whom it may concern:

Be it known that we, PORTEUS R. CUNNINGHAM and CHARLES H. HOWLAND-SHERMAN, citizens of the United States, residing at 5 Washington, District of Columbia, have invented certain new and useful Improvements in Invertible Fluid-Batteries; and we do hereby declare the following to be a full, clear, and exact description of the invention, such 10 as will enable others skilled in the art to which it appertains to make and use the same.

This invention relates to improvements in primary batteries for electric lamps. It has particular reference to that class of lamps 15 known as the "portable" variety, which may be used in connection with vehicles, such as side lights for carriages or lamps for bicycles.

The objects of the invention are, first, to reduce or minimize what is commonly called 20 "local action" and polarization; secondly, to provide for the ready insertion and removal of the electrodes of said battery and for maintaining them immovably in place when inserted.

25 With these and other objects and advantages in view the construction consists, essentially, in an invertible lamp; means carried thereby for securing said lamp to some stationary part of a vehicle and for permitting 30 it to be adjusted vertically, to throw the rays up or down, and to rotate said lamp, whereby it may be inverted; novelly-constructed removable electrodes with means for securing them immovably within the cells of the battery and for connecting the said electrodes 35 with the said translating device, and an automatic gas-vent, all of which will more fully appear from the description and claims to follow and the illustrations in the accompanying 40 drawings, in which—

Figure 1 is a central longitudinal sectional view on the line 2 2 of Fig. 3, showing the interior construction. Fig. 2 is a side elevation of the lamp designed for use in connection with a bicycle. Fig. 3 is a sectional view on the line 3 3 of Fig. 1. Fig. 4 is a diagrammatic view showing the system of wiring. Fig. 5 is a transverse sectional view of the hard-rubber battery-box. Fig. 6 is a 45 transverse sectional view on the line 6 6 of

Fig. 1, showing lamp-bracket with the escutcheon-piece thrown back in dotted lines. Fig. 7 is a side elevation of one of the electrodes, (the zinc.) Fig. 8 is a top plan view of the same. Fig. 9 is a transverse sectional view of the cap and lining, showing the diametric rib. Fig. 10 is a top plan view of the hard-rubber battery-box, showing the transverse partition which the diametric rib in the lamp-top is designed to contact with; Fig. 60 55 Fig. 11, detail views of the valve and gas-pipe cap; Fig. 12, detail views of the electrode-clamp; Fig. 13, detail views of spider-catches; Fig. 14, detail view of the contact-plates.

Like numerals of reference designate like 65 parts throughout all the figures of the drawings.

1 represents the outer casing of the lamp, which may be of any form or design and closed at the bottom, the word "bottom" in 70 this connection being used to represent that portion of the lamp which is closed in contradistinction to the opposite end, which is provided with a novelly-constructed hermetically-sealing cap 2, made the subject of another application for Letters Patent by us and filed September 19, 1896, Serial No. 606,407, and to said cover or top singly no claim is made in this application. This cap is formed with the metallic part 3 and interior flexible lining 4, provided with an annular flange 4^a, conforming in cross-section to that of a boss or bead of the rim of the battery-box, and a diametrical rib or partition 5. Said cap is hinged at 6 to the switch-covering 7, which is secured to the back 75 of the casing 1 and extends to the bead formed on the casing near the bottom to maintain the symmetry of the design. A spring-catch 8, carried by the lamp-casing, is provided to secure the lamp-top against dislocation by jolting or rough usage. Snugly fitting within this casing 1, which is shown here as tubular, is a hard-rubber battery-box 10, recessed, as shown at 11, for the reception of the holophotic reflector 12 and lamp-rosette 13, carrying the lamp-globe 14.

15 is a vertical partition extending from the bottom of the hard-rubber battery-box 10 up to and flush with its upper rim. This partition 15 extends diametrically across said 100

battery-box in line with the reflector and switch-covering 7, and thereby divides said box into two compartments or cells 16 and 17.

18 is an orifice in this partition to permit 5 the passage of gas usually generated in primary batteries to a certain extent, and located near the same in the cell 17 is a gas-vent 19. This gas-vent consists of a gas-pipe 20 and a cap threaded on the top thereof to form a 10 valve-chamber and having a central perforation 21. In the interior of this cap is formed a valve-seat 22, against which is normally pressed a valve 23. This valve is provided with a depending stem, around which is coiled 15 a spring 24, abutting against the valve, and a perforated disk 25, seated on the upper edge of the gas-pipe 20. The height of this gas-pipe and cap is such that the central opening 21 is above a central plane passed transversely 20 through the battery-box and above the level of the electrolyte when the lamp is rotated into position for use, as shown clearly in Fig. 2.

Attention is called to detail views Fig. 11, 25 which show the valve with diametrically-disposed grooves in its sides and an upper extension 52, adapted to enter the opening 21, which is also provided with diametrically-disposed grooves, and to seal it when the valve 30 is not acted upon by the pressure of accumulated gas. This forces said valve downward against the tension of the coil-spring and permits the escape of the imprisoned gas through the grooves in the opening 21 and those formed 35 in the periphery of the valve out through the perforations of the valve disk or plate 25, down through the gas-pipe, and out of the lamp through the bottom of the casing 1. This pipe is provided with threads a short 40 distance from its lower end and is designed to thread into the bottom of the battery-box and the projecting end to extend into a registering perforation in the bottom of the casing 1. This construction renders the gas-pipe 45 removable with the battery-box.

Formed on the sides of the central partition 15 and the interior walls of the lamp-recess 11 (speaking relatively to the interior of the battery) are the parallel vertical ribs 26, which are 50 spaced apart for the vertical insertion of the arc-shaped cathode 27 and anode 28, which are formed with the slots 29, extending vertically up from the bottom to a point approximately near their centers. This permits a free circulation in each cell of the electrolyte. This electrolyte may consist of a solution of bichromate of potash and sulfuric acid in suitable proportions, although it is obvious that any other of the well-known solutions will suit the purposes of this invention equally as well. These electrodes rest upon semicircular mats made of any suitable material, such as soft rubber. These mats are designated as 30. As shown clearly in Figs. 3, 5, and 10, the hard-rubber 65 battery-cells are provided with the diametrically-disposed lugs 31, formed on the central partition, and lugs 32, formed on the in-

terior walls of the respective cells. These lugs are recessed, as shown by dotted lines, and are adapted to receive the hard-rubber 70 removable clamps 33. (Shown in detail in Fig. 12.) These non-conductive clamps are provided upon their lower faces with grooves 34, designed to register with the tops of the arc-shaped zincs and carbons and to permit 75 the passage therethrough of the wires which connect the electrodes of both cells with the translating device. These clamps have the reduced end portions 35 to permit a hinge movement in the lugs 31 and with knobs 36 80 to facilitate their placement and displacement accordingly as the electrodes are to be immovably secured in place within their respective cells or to be removed for any purpose whatever. Fastened to the upper edges of 85 the cathodes, directly beneath this clamp 33, are the non-corrosive metallic contact-plates 37, which are bent downwardly or flanged on both sides of the arc-shaped cathodes to be more firmly secured against displacement, 90 and to the tops of each are connected the ends of a wire or other conductor 38, passing for a portion of its length out into the lamp-recess 11. The object of this is to connect all the 95 cathodes of each cell. Connected to the anode of cell 16 by means of the binding-post 39 is a wire 40, passing through the wall of the recess 11 and over to the common connection between the cathodes of the opposite cell, where it is electrically connected to that portion which passes on the outside of the wall of the recess. Where these wires pass through the walls of the recess, the perforations are 100 well sealed. Connected to the anodes of this latter cell 17 by means of a binding-post 41 is 105 a wire 42, passing through the contiguous wall of the recess and connected with the lamp-rosette 13, in which is threaded a globe 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 tact with said plates by means of the switch-knob 50, working in the elongated vertical slot 51.

Secured to the switch-covering 7 in any suitable manner so as to clear the slot 51 and approximately in a line with the transverse balancing center is an adjustable hinge-bracket 53, comprising the hinge members 54 and 55, adjustably secured by the headed hinge-bolt 56 and the king-post clamp 57. The hinge-bolt 56 passes through an axial perforation 58 in the hinge member 55 and is threaded into a registering axial perforation 59 in the hinge member 54. The working faces of these hinge members are radially serrated, as at 60, to more firmly bind when the hinge-bolt 56 is tightened for any new adjustment of the lamp. Interposed between the hinge member 55 and the head of the hinge-bolt is a washer 61.

Formed integral with the hinge member 55 is the king-post clamp 57, comprising a stationary arc-shaped member 63, slightly more than semicircular, and the hinged member 64, slightly less in its arc than a semicircle. These clamp members or arms 63 and 64 are hinged at 65, as shown in Fig. 6, and are provided each with felt lining 66 to prevent abrasion of the enamel on the steering-post tube of the bicycle when the clamp is secured in position. The clamping members or arms are provided with projecting jaws 67 on the clamping member 63 and ears 68 on the clamping member 64. Passing vertically downward through perforations in the ears 68 is a pin 69, on which is swung a clamping-bolt 70, threaded on its opposite end and carrying a washer and tightening-nut 71. This bolt is adapted to be swung into position between the jaws 67 when the clamping members 63 and 64 are adjusted upon the steering-post tube or king-post and to securely clamp or bind the same upon this tube. The jaws 67 are provided with the lips 72, extending laterally therefrom, and they are adapted to securely maintain the washer and nut in place upon the jaws 67. The clamping members or arms 63 and 64, when conforming exactly to the arcs of one circle, have the meeting ends separated by sufficient space to permit of the adjustment of this bracket to steering-post tubes of less diameter than the standard. Between this adjustable hinge-joint 53 and the lamp is located a swivel-joint 73, comprising circular plates 74 and 75, carried, respectively, by the hinge member 54 and the switch-covering 7. Formed integral with the circular plate 74 is an axial stud 76, designed to revolvably fit an axial perforation in the swivel-plate 75 and to be headed upon the opposite face thereof and in the interior of the body-like attaching portion 77. It will be seen from this construction of hinge and swivel-bracket that provision is made for a rotation of the lamp, whereby it may be completely inverted and the electrodes freed from the electrolyte, thereby minimizing polariza-

tion and preventing local action. By the adjustment afforded through the medium of the hinge members 54 and 55 and the hinge-bolt 56 the lamp may be aimed at any angle necessary to properly light the path of the rider.

Secured to the lamp-rosette in the recess 11 is a socket which is internally threaded to receive an exteriorly-threaded and interiorly-threaded tubular extension 78 or projection, carried on the rear of the holophotic reflector 12. Threaded into the extension 78 is the plug of the lamp 14. At a proper distance from this lamp is removably secured by means of the lens-spider 81 a refracting-lens 82. This lens-spider 81 consists of the inclosing-rim 83 and the upwardly and downwardly projecting radial arms 84, having the laterally-projecting pins 85, engaging with the spider-catches 86, formed with the jaws 87 for the retention of the pins above referred to. The parabolic reflector has the dust-proof glass face 88 secured thereto by an annular screw-threaded rim 89.

This completes the description of the improved vehicle-lamp and primary battery, and from the foregoing description, in connection with the accompanying drawings, it will be readily observed that polarization is minimized by the provision of an invertible lamp of great simplicity and utility and that the efficiency of the same is heightened by the prevention of local action when the battery is not in use and by the construction and arrangement of the removable electrodes, and, further, that the candle-power produced by this primary battery is greatly increased by the addition of a holophotic reflector.

The operation of the lamp and of the various parts contained therein will be obvious from the foregoing, and more detailed description is rendered unnecessary.

We do not desire to limit ourselves to the precise details of construction herein shown and described, but reserve to ourselves the right and privilege to alter the same within the bounds of mechanical ingenuity without departing from the spirit of our invention.

Having thus described our invention, what we claim as new, and desire to secure by Letters Patent, is—

1. In an invertible fluid-battery, the combination of a closed casing, electrodes, of less height than the interior of the casing, removably inserted therein and designed to be freed from the electrolyte, when the casing is inverted, and retaining means engaging with the tops of the said electrodes but insulated therefrom, and interlocking interiorly with the casing to secure said electrodes in a fixed position and against displacement when the casing is inverted.

2. In an invertible fluid-battery, the combination of a suitably-closed casing, provided with one or more cells, electrodes of less height than the interior of the casing, removably inserted therein and designed to be freed from the electrolyte, when the casing is

inverted, and retaining means engaging with the tops of the said electrodes but insulated therefrom, and interlocking interiorly with the casing to secure said electrodes in a fixed position and against displacement when the casing is inverted.

3. In an invertible fluid-battery, a suitable receptacle having an annular boss or bead on its rim, and a hermetic closure, comprising a top and a flexible lining secured therein and provided with a depending, annular portion or flange, adapted to tightly inclose the mouth of the receptacle and a circumferential enlargement upon the interior of the depending portion or flange, adapted to tightly flex into the circumferential groove below the bead on the receptacle, when the closure is pressed into place; in combination with electrodes, of less height than the interior of the casing, removably inserted therein and designed to be freed from the electrolyte when the casing is inverted, and non-conductive retaining means extending across the tops of the electrodes and fastening the same to the interior of the casing, whereby they are secured against displacement when the casing is inverted.

4. In an invertible fluid-battery, the combination of a closed casing, electrodes of less height than the interior of the casing, inserted therein and removably engaging with the interior walls of the casing, gates or openings for the free circulation of the electrolyte about the electrodes, and retaining means engaging with the tops of the said electrodes but insulated therefrom, and interlocking interiorly with the casing to secure said electrodes in a fixed position and against displacement when the casing is inverted to free the electrodes from the electrolyte.

5. In an invertible fluid-battery, the combination of a closed casing, electrodes, of less height than the interior of the casing, removably inserted therein and designed to be freed from the electrolyte when the casing is inverted, non-corrosive, conducting-plates removably secured to the said electrodes and electrically connected with a translating device on the outside of the casing, and retaining means engaging with the tops of the said electrodes but insulated therefrom, and interlocking interiorly with the casing to secure said electrodes in a fixed position and against displacement when the casing is inverted.

6. In an invertible fluid-battery, the combination of a closed casing, electrodes, of less height than the interior of the casing, inserted therein and removably engaging with the interior walls of the casing, gates or openings for the free circulation of the electrolyte about the electrodes, retaining means engaging with the tops of the said electrodes but insulated therefrom, and interlocking interiorly with the casing to secure said electrodes in a fixed position and against displacement when the casing is inverted to free the electrodes from

the electrolyte, and electrical connections between said electrodes and a translating device on the outside of the casing.

7. In an invertible fluid-battery, the combination of a suitable closed casing, electrodes, of less height than the interior of the casing, removably inserted therein and designed to be freed from the electrolyte when the casing is inverted, and non-conductive clamps extending across the tops of the electrodes, and engaging removably with recessed lugs projecting from the interior surface of the casing, to secure said electrodes against displacement when the casing is inverted, substantially as described.

8. In an invertible fluid-battery, the combination of a closed casing, vertically-disposed spacing-ribs projecting from the interior thereof, electrodes, of less height than the interior of the casing, removably inserted therebetween, oppositely-disposed, recessed lugs projecting interiorly from the casing, and non-conductive retaining means engaging with the said lugs and with the said electrodes to secure them in position between the spacing-ribs and against displacement when the casing is inverted to free them from the electrolyte, substantially as described.

9. In an invertible fluid-battery, a suitable receptacle provided with one or more cells, and having an annular boss or bead on its rim, and a hermetic closure therefor, comprising a top and a flexible lining secured therein and provided with a depending, annular portion or flange, adapted to tightly inclose the mouth of the receptacle and a circumferential enlargement upon the interior of the depending portion or flange, adapted to tightly flex into the circumferential groove below the bead on the receptacle, when the closure is pressed into place; in combination with electrodes, of less height than the casing, removably inserted therein, and designed to be freed from the electrolyte when the casing is inverted and non-conductive retaining means extending across the tops of the electrodes and fastening the same to the interior of the cells, whereby the said electrodes are secured against displacement when the casing is inverted, substantially as described.

10. In an invertible fluid-battery, the combination of a closed casing, electrodes, of less height than the interior of the casing, removably inserted therein and designed to be freed from the electrolyte when the casing is inverted, non-conductive retaining means engaging with the tops of the electrodes and interlocking interiorly with the casing to secure the said electrodes against displacement, and an automatically-acting gas-vent, for the escape of accumulated gas.

11. In an invertible fluid-battery, the combination of a closed casing, electrodes, of less height than the interior of the casing, removably inserted therein and designed to be freed from the electrolyte, when the casing is inverted, and non-conductive retaining

means engaging with the tops of the said electrodes, and interlocking interiorly with the casing to secure said electrodes in a fixed position and against displacement when the casing is inverted and a lamp-bracket comprising pivoted clamping-arms, a locking device for said arms and a universal connection between the body of the closed casing to be supported and the said clamping-arms, substantially as described.

12. In an invertible fluid-battery, a suitable receptacle provided with one or more cells, and having an annular boss or bead on its rim, and a hermetic closure therefor, comprising a top and a flexible lining secured therein and provided with a depending, annular portion or flange, adapted to tightly inclose the mouth of the receptacle and a circumferential enlargement upon the interior 20 of the depending portion or flange, adapted to tightly flex into the circumferential groove below the bead on the receptacle, when the closure is pressed into place; in combination with electrodes, of less height than the receptacle, removably inserted therein, and designed to be freed from the electrolyte when the receptacle is inverted, and non-conductive retaining means extending across the tops of the electrodes and fastening the same to 30 the interior of the cells, whereby they are secured against displacement when the casing is inverted, substantially as described.

13. In an invertible fluid-battery, the combination of a receptacle, divided into cells, by 35 means of one or more partitions, a hermetically-sealing, removable top therefor, electrodes, of less height than the receptacle, seated in the lower parts of the cells, and designed to be freed from the electrolyte, when 40 the receptacle is inverted, and clamps extending across the tops of the electrode of each cell, and engaging removably with retaining means, on the interior walls of the respective cells, to secure said electrodes against 45 displacement when the receptacle is inverted, substantially as described.

14. In an invertible fluid-battery, a suitable receptacle provided with one or more cells, and having an annular boss or bead on 50 its rim, and a hermetic closure therefor, comprising a top and a flexible lining secured therein and provided with a depending, annular portion or flange, adapted to tightly inclose the mouth of the receptacle and a circumferential enlargement upon the interior 55 of the depending portion or flange, adapted to tightly flex into the circumferential groove below the bead on the receptacle, when the closure is pressed into place; in combination with electrodes, of less height than the receptacle, removably inserted therein, and designed to be freed from the electrolyte when 60 the receptacle is inverted, non-conductive retaining means extending across the tops of 65 the electrodes and fastening the same to the interior of the cells, whereby they are secured against displacement when the casing is in-

verted, an opening between the cells for the circulation of gas and a gas-vent for the escape of the accumulated gas from the receptacle, substantially as described.

15. In an invertible fluid-battery, the combination of a receptacle having a boss or bead on its rim, and divided into cells, by means of one or more partitions, electrodes, of less 70 height than the receptacle, secured in the lower parts of the cells and designed to be freed from the electrolyte, when the receptacle is inverted, a hinge-bracket, a swivel connection between it and the said receptacle, 80 whereby it can be inverted, means for securing said hinge-bracket to a vehicle, and a hermetically-sealing, removable top therefor, comprising a flanged cover, and a lining secured therein and provided with an annular 85 flange whose interior is epicycloidal in cross-section and designed to tightly adhere to the bead or boss of the receptacle when sprung over it, substantially as described.

16. A casing for an invertible fluid-battery 90 consisting of a suitable receptacle, having a central partition and a boss or bead upon the outside of the rim, and a hermetically-sealing closure, comprising a hinged top and a permanent lining secured within said top and 95 formed with a diametrically-disposed rib, parallel with the upper edge of the partition in the said receptacle, a depending annular flange, arc-shaped in cross-section to form a constriction, adapted when sprung over the 100 bead or boss on the receptacle, to tightly adhere to the curvature of the same, substantially as described.

17. A casing for an invertible fluid-battery consisting of a suitable receptacle, having a 105 central partition, and a boss or bead upon the outside of the rim, a hermetically-sealing closure, comprising a hinged top and a permanent lining, secured within said top and formed with a diametrically-disposed rib, parallel with the upper edge of the partition in the said receptacle, a depending annular flange, arc-shaped in cross-section to form a constriction adapted, when sprung over the 110 bead or boss on the receptacle, to tightly adhere to the curvature of the same, and means for locking said cover to said receptacle, substantially as described.

18. The herein-described gas-vent, comprising a valve-chamber having an opening in one 120 end, oppositely-disposed channels or grooves in the sides of said opening, a conical valve-seat, and a spring-actuated valve, correspondingly shaped to fit said seat, a base to said valve slidably fitting within the said valve-chamber and having oppositely-arranged 125 channels or grooves in its periphery, a projection on said valve, slidably fitting the opening in the valve-chamber, and a perforated disk, closing the opposite end thereof.

19. The herein-described gas-vent, comprising a valve-chamber having an opening in one end, oppositely-disposed channels or grooves in the sides of said opening, a conical valve-

seat, and a spring-actuated valve correspondingly shaped to fit said seat, a base to said valve slidably fitting within the said valve-chamber and having oppositely - arranged 5 channels or grooves in its periphery, a projection on said valve, slidably fitting the opening in the valve-chamber, and a perforated disk at the opposite end of the valve-chamber, in combination with an inclosing receptacle 10 and a pipe connection between the said valve-chamber and the exterior of the said receptacle, substantially as described.

20. In an invertible fluid-battery, the combination of a suitable receptacle provided with 15 one or more cells, a hermetic closure therefor, vertically-disposed spacing-ribs projecting from the interior thereof, electrodes, of less height than the interior of the cells, removably inserted between said ribs, oppositely-disposed, recessed lugs projecting interiorly from the casing, non-conductive clamps 20 extending across the tops of the electrodes and engaging removably with the said lugs and with the said electrodes to secure them in position between the spacing-ribs and against 25 displacement when the receptacle is inverted, a passage between the cells for the circulation of gas, and a gas-vent for the escape of the same from the receptacle, comprising a valve-chamber having an opening in one end and 30 projecting within said receptacle, oppositely-disposed channels or grooves in the sides of said opening, a conical valve-seat and a spring-actuated valve, correspondingly shaped to fit 35 said seat, a base to said valve, slidably fitting within the valve-chamber and having oppo-

sitely-arranged channels or grooves in its periphery, a projection on said valve, fitting slidably into the opening in the valve-chamber, and a perforated disk located in the opposite end of the said chamber, substantially as described. 40

21. As a new article of manufacture, the herein-described battery-box, comprising an open, cylindrical vessel of non-conductive 45 material, formed integrally with a central partition as 15, dividing the vessel into two compartments or cells, an inset chamber or recess as 11, opening exteriorly of the vessel, parallel and vertical spacing-ribs as 26, projecting interiorly from the walls of the partition and recess or chamber, electrodes fitting between said ribs, the diametrically opposite, undercut lugs, projecting from the walls of the partition and of the vessel, and 50 clamps engaging with said lugs and with the tops of the electrodes to fasten them in place, substantially as and for the purposes specified. 55

In testimony whereof we affix our signatures in presence of two witnesses. 60
